INSULATIVE COVER FOR ELECTRICAL CONDUCTORS

Frederick William Wahl, Middletown, Pa., assignor to
AMP Incorporated, Harrisburg, Pa.

Continuation of design applications Ser. No. 20, and Ser.
No. 88,264, Nov. 30, 1965. This application Aug. 24,
1966, Ser. No. 3,906

Term of patent 14 years

(Cl. D26—10)

FIGURE 1 is a left, end, top and front perspective view of an insulative cover for electrical conductors, showing one form of my new design wherein one section of the insulative cover is larger than the other section and each end is continuous to surround electrical conductors extending therethrough;

FIGURE 2 is a front elevational view of the form shown in FIGURE 1;

FIGURE 3 is a rear elevational view of the form shown in FIGURE 1;

FIGURE 4 is a top plan view of the form shown in FIGURE 1;

FIGURE 5 is a bottom plan view of the form shown in FIGURE 1;

FIGURE 6 is a left end elevational view of the form shown in FIGURE 1, the right end being substantially a mirror image thereof;

FIGURE 7 is a front, top and right end perspective view of an insulative cover for electrical conductors, showing another form of my new design wherein each section of the insulative cover is identical and each end includes individual frusto-conical sections surrounding electrical conductors extending therethrough;

FIGURE 8 is a front elevational view of the form shown in FIGURE 7;

FIGURE 9 is a rear elevational view of the form shown in FIGURE 7;

FIGURE 10 is a top plan view of the form shown in FIGURE 7;

FIGURE 11 is a bottom plan view of the form shown in FIGURE 7; and

FIGURE 12 is a right end elevational view of the form shown in FIGURE 7, the left end being substantially a mirror image thereof.

This application is a continuation of U.S. patent applications, Ser. Nos. D.20 and D.88,264, filed Nov. 30, 1965, now abandoned.

I claim:

The ornamental design for an insulative cover for electrical conductors, substantially as shown and described.
